(57) **CLAIM**

I claim the ornamental design for a clip, as shown and described.

DESCRIPTION

FIG. 1 is a front perspective view of a clip configured for attachment to an exemplary harness and configured to receive an exemplary gas detector in accordance with the new design;

FIG. 2 is a front perspective view of the clip configured for attachment to an exemplary harness and configured to receive an exemplary gas detector, wherein the clip is shown attached to the exemplary harness in accordance with the new design;

FIG. 3 is a front perspective view of the clip configured for attachment to an exemplary harness and configured to receive an exemplary gas detector, wherein the clip is shown attached to the exemplary harness, and the exemplary gas detector is shown positioned in the clip in accordance with the new design;

FIG. 4 is a front elevation view of the clip configured for attachment to an exemplary harness and configured to receive an exemplary gas detector in accordance with the new design;

FIG. 5 is a rear elevation view thereof;

FIG. 6 is a right side elevation view thereof;

FIG. 7 is a left side elevation view thereof;

FIG. 8 is a top plan view thereof; and,

FIG. 9 is a bottom plan view thereof.

The broken lines illustrate portions of the clip and environment that form no part of the claimed design.
